UNITED STATES PATENT OFFICE.

CLARENCE B. DAVIDSON, OF SAN FRANCISCO, CALIFORNIA.

MANIFOLDING-BOOK AND THE METHOD OF MANIFOLDING.

1,392,748.

Specification of Letters Patent.

Patented Oct. 4, 1921.

Application filed October 7, 1918. Serial No. 257,307.

To all whom it may concern:
Be it known that I, CLARENCE B. DAVIDSON, a citizen of the United States, and a resident of the city and county of San Francisco, State of California, have made a new and useful Invention—to wit, Improvements in Manifolding-Books and the Methods of Manifolding; and I do hereby declare the following to be a full, clear, concise, and exact description of the same.

Among the objects of the invention is to provide a triplicating book that is simple and convenient in operation and that will eliminate any back hand or off set copies on the reverse sides of any of the record sheets, after the original impression has been taken. Other objects and advantages will appear as this description progresses.

In this specification and the annexed drawings, the invention is illustrated in the form considered to be the best, but it is to be understood that the invention is not limited to such forms, because it may be embodied in other forms; and it is also to be understood that in and by the claims following the description, it is desired to cover the invention in whatsoever form it may be embodied.

In the accompanying one sheet of drawings—

Figure 1 is a plane view of a piece of carbon paper forming part of this invention.

Fig. 2 is a perspective view from above of a manifold book constructed in accordance with this invention, with the carbon incorporated therein and shown in a slightly elevated position before folding into the record sheet below.

In detail the construction illustrated in the drawings comprises a manifold book formed into sections as shown in Fig. 2, each section is composed in the following order: Under the top cover, if any, a special carbon sheet coated on its opposite sides on reverse sides of its transverse center and about two-thirds ($\frac{2}{3}$) the length of the record sheets is so placed that the first carbonized half A faces downward and will be attached to the stub, so that the other half B of the carbon sheet facing upward, will fold over it when in use. Below this carbon 1 are a number of sheets of paper 2, that extend the full length of the book and have perforated lines as shown in 4, 5 and 6. About mid-

way in the book is placed a heavy flexible paper 3, immediately above another carbon sheet like the first one in the book. The number of legible manifolds possible from a single carbon sheet being known, the pages of the book are proportioned accordingly and the carbons may be distributed throughout the book by interposing them between a given number of pages. The sheet of heavy paper 3 superimposed above each carbon sheet prevents the pencil or pen pressure in manifolding, registering on the sheet below it. This heavy flexible paper 3 is the same length as the carbon and is perforated at the stub only.

The present disclosure is confined to a triplicating book, so bound that it is intended that all three sheets be torn from the stub before a second sheet is operated upon. This is necessitated by the back of the carbon being bound in the stub. It is obvious however, that by utilizing a loose carbon, not bound in the stub, that the triplicate impressions may be left bound to the stub and bent backward while the carbon is inserted above the succeeding full length page, the mode of operation being the same in either instance. The binding in of a multiplicity of carbons with superimposed heavy paper 3 is of course optional and is not essentially a part of this invention, it being a good expedient in manifolding books containing a number of pages in excess of the number that a single sheet of carbon will give a good transfer impression upon.

The carbons, the record sheet and the heavy flexible paper sheet are all bound together at the stub 7 by wire staples or other suitable means such as 8 and 9. The perforated line 10 on the stub facilitates the tearing off of the sheets easily. The sheets are likewise perforated or scored as at 4, between the division adjacent the stub and the intermediate division, that receives the original writing, and is similarly perforated at 5 between the intermediate division and the last division of the sheet that becomes the duplicate. The second score line or perforation 4 should fall immediately beneath the division of the carbon between the blank and the carbonized surfaces thereon.

This invention is operated substantially as follows:

The record sheet is folded first along the

perforated line 5, thus folding the outer division of the sheet backward and into superimposed position over the end of the carbon sheet B, that faces upward. The whole sheet including the carbon is then folded on the perforated line 4, which faces the portion B downward and superimposes the outer section or duplicate immediately above the portion C of the carbon, which leaves the portion A of the carbon superimposed above the first division of the sheet that will become the triplicate. These various divisions are similarly printed or lined to register when the sheet is folded up. By this arrangement the carbonized surface A of the carbon sheet lies immediately against the page upon which the triplicate impression is to be registered, the uncoated opposite side C of the carbon protecting the sheet immediately above from any impression such as is made when a double coated or a carbon sheet coated on both sides is used, and the uncoated portion D similarly protects the original. By this invention the material disadvantages following the use of a sheet coated on both sides are obviated. First, such a double coated carbon is disagreeable to handle as it smudges the fingers of the operator and likewise the sheets against which it lies. Further duplicate and triplicate having carbon impressions on both sides smudge the others when packed or filed away; or when the stubs are left in the book and further impressions are taken above them. The present invention gives a clear record on one side of the record sheet only. The original record is impressed on the inverted middle section of the sheet when folded in the manner described. This record is transferred through the carbon B to the end section of the sheet immediately beneath which is the duplicate, being the first impression under the original. The impression continues on through the carbon sheet A to the first sheet joined to the stub 7, which becomes the triplicate impression of the original record. When the record is complete the leaf is unfolded to full length, the carbon turned back at the stub and the complete record sheet torn from the stub on the perforation line 6. This shows the triplicate and the duplicates facing upward on the opposite ends of the sheet, and the original, on the intermediate section of the sheet, facing downward. The sheets may now be separated on the perforated lines 4-5 into the three separate divisions forming the original, the duplicate and the triplicate of the record, to be disposed of as desired.

Having thus described this invention,

what I claim and desire to secure by Letters Patent is:—

1. A manifolding book comprising a plurality of record sheets and carbon sheets bound together, each record sheet having two-fold lines and foldable into end and intermediate sections, each carbon sheet having a single fold line and two carbon surfaces, the carbon surfaces being placed on opposite faces of the sheet and on opposite sides of the fold line; one of said carbon surfaces facing downwardly on an end section of said record sheet and the other carbon surface facing away from the intermediate section, whereby the remaining end section may be folded over said last mentioned carbon surface and said last mentioned end section and intermediate section folded over onto the remaining end section, whereby an impression on one side of the intermediate section is made to appear on the opposite side of the end sections.

2. A manifolding book comprising a plurality of record sheets and carbon sheets bound together, each record sheet having two fold lines and three record sections; each carbon sheet having a single fold line and two carbon surfaces, equal in length to two sections of said record sheet, the carbon surfaces being placed on opposite faces of the sheet and on opposite sides of the line of the fold, one carbon surface facing downward over an end portion of the record sheet and the opposite carbon surface facing upwardly away from the intermediate section of the same record sheet, whereby the remaining end section may be folded over said last mentioned carbon surface, and said end and intermediate section folded over onto the remaining end section, whereby an impression on one side of the intermediate section is made to appear on the opposite side on the end sections.

3. A manifold book for executing triplicate records comprising record sheets and carbon sheets bound together, each record sheet having two weakened lines of fold, and three record sections, and each carbon sheet having a single weakened line of fold and two carbon surfaces, the carbon surfaces being placed on opposite faces of the sheet and on opposite sides of the line of fold, in such manner that impressions will be recorded on the upper faces of the record sheet only.

In testimony whereof I affix my signature in presence of two witnesses.

C. B. DAVIDSON.
